By Fisher Towle Clapp & Sons Atty's.

UNITED STATES PATENT OFFICE.

ERNST MAHLER, OF NEENAH, WISCONSIN, ASSIGNOR TO PAPER PATENTS COMPANY, OF NEENAH, WISCONSIN, A CORPORATION OF WISCONSIN.

PAPER-MAKING MACHINERY.

Application filed May 4, 1925. Serial No. 27,724.

This invention relates to paper-making machinery but more particularly to calendering mechanism and has for its primary object to provide a simple, and efficient device for applying pressure to the rolls of a calendering stack.

Further objects of my invention are to provide adequate and uniform pressure on the rolls, to facilitate the adjustment and release of the pressure, to eliminate the necessity for readjustment of the pressure after release, to prevent injury to the stack, and in general to provide a new and improved pressure device for a calendering stack.

The many other objects and advantages of my invention will be better understood by reference to the following specification when considered in connection with the accompanying drawings illustrating a selected embodiment thereof, in which:

Fig. 1 is an end elevation of a calendering stack having incorporated therein a pressure device embodying the principles of my invention.

Fig. 2 is a side elevation.

Fig. 3 is an enlarged elevation of a portion of the pressure device.

Fig. 4 is a vertical section on the line 4—4 of Fig. 3.

Fig. 5 is a top plan view of the portion of the mechanism shown in Fig. 3, and

Fig. 6 is a horizontal section on the line 6—6 of Fig. 4.

Referring to the drawings, the stack 10 comprises the usual rolls 11 and end frames 12. One of these rolls is driven by suitable gearing and the other rolls of the stack are frictionally driven therefrom. The bearings 13 of the rolls 11 are vertically slidable in the frames 12. Only sufficient mechanism of this stack has been shown to enable the construction and mode of operation of my improved hydraulic pressure device to be readily understood as the stack is of the well-known super-calender type.

The weight of these rolls is generally insufficient to produce the proper glaze on the paper and it is customary in the art to apply additional pressure. In the present invention, a hydraulic pressure mechanism is provided which acts upon the bearings of the upper roll. A lever as 14 is pivotally mounted at 15 on each of the end frames 12 and a pull rod as 16 is connected to the free outer end of this lever. Vertically

movable plungers as 17 act between the under faces of these levers and the corresponding bearings 13. As the mechanism for operating each of these pull rods is the same, only one will be described in detail.

The rod 16 preferably comprises two sections 18 and 19 connected by a turn buckle as 20 to permit the length of the rod to be adjusted. This turn buckle is provided with a hand wheel 21 to facilitate its operation. The lower extremity of the section 19 is pivotally connected to the hydraulic pressure device 22.

The present embodiment of my hydraulic pressure device 22 includes a cylinder 24, the bottom end of which is pivotally connected to the end frame 12, so as to permit a limited swinging movement. Such pivotal connection comprises a pin 25 which passes through an apertured lug or extension 26 on the bottom of the cylinder and similar lugs 27, 27 on the end frame 12. A head 28 is secured upon the cylinder by bolts 29 or other suitable means.

A piston 31 operates within the cylinder 24 and a piston rod 32 is attached to this piston. The downward travel of the piston within the cylinder is limited by a stop 33 which in the present embodiment consists of cross ribs as 34 disposed at substantially a right angle and integral with the cylinder. A stuffing box 36 of suitable type is mounted in the cylinder head. Fluid under pressure is admitted to the cylinder through a port 37 which also acts as the exhaust. A pipe as 38 connects the ports 37 of the hydraulic devices at opposite ends of the stack and a pipe 39 communicates with this pipe 38. A three-way valve 40 is provided to permit the pipe 39 to be selectively connected with the accumulator or source of supply of fluid under pressure or with a sewer or discharge outlet. For convenience, the piping has been illustrated as above the flooring and adjacent to the stack mechanism but in practice it is preferably located beneath such flooring and at a point more remote from the stack.

The lower section 19 of the pull rod 16 is connected to a cross-head 45 by the pin 46 which passes through an eye 47 on the rod and eyes 48, 48 on the cross-head. The cross-head is secured to the upper extremity of the piston rod 32, and is slidable on spaced vertical parallel guide posts 49, 49 fixed in

the cylinder head 28. Thus the lower rod-section 19 is prevented from turning when the hand wheel 21 is rotated.

- In the operation of the device, pressure is applied to the rolls of the stack by turning the valve 40 to connect the pipe 39 with the accumulator. This admits pressure fluid to the cylinder above the pistons and forces the piston down against its stop, and results in a downward pull on the rods 16 depending in amount upon the adjustment of the hand wheel. The pressure actually exerted on the rolls of the stack is the pull on the rods 16 as multiplied by the levers 14.
- 15 The pressure of the fluid in the accumulator is always more than sufficient to force the piston against its end stop under all ordinary conditions of working. Therefore, assuming that such pressure is always maintained in the accumulator, the adjustment of the pressure on the rolls to suit varying conditions of operation will always be effected by means of the turnbuckle controlled by the hand wheel 21.
- 25 When it is desired to relieve the pressure or super-pressure which is applied to the stack through the pull rods 16, for example at the beginning of a run or in case the paper breaks, the operator turns the valve 40 into the position where the cylinder is connected with the waste pipe instead of with the accumulator. Thus, there will be nothing holding the piston against its end stop and the levers 14 will be free to rise. This permits the paper to be inserted between the rolls, which would not be possible if the super-pressure prevailed. It will be observed that there is no necessity to adjust or to re-adjust the hand wheels when starting the run or effecting a paper change or repair, since the cylinder and its piston, in this respect, merely function as a quick detachable connection between the end of the pull rod 19 and the frame lugs 27.
- 45 In addition to the advantage that the necessity of adjusting the hand wheels after they have once been set to the proper pressure for the class of paper being operated upon, is eliminated, the improved hydraulic arrangement has another very important advantage. It has been stated that at all times the pressure of the cylinder under normal operating conditions is more than sufficient always to force the piston against its stop.
- 55 Such pressure, however, is limited, or the piston area is limited, to provide a roll pressure which is insufficient to cause breakage of the roll journals or other parts of the stack. Hence, the hydraulic cylinder and piston operate at all times as a safety device, and if the paper instead of passing through the rolls as it should, should happen to start wrapping around one of the rolls, the rise in pressure due to the increasing diameter of the paper covered roll would be arrested as

soon as a certain fixed amount had been exceeded. Thereafter, the increase in diameter of the roll would merely cause the pistons to rise in the cylinders and force the hydraulic fluid back into the accumulator.

The advantages of this hydraulic arrangement will be manifest to those skilled in the art. For example, instead of making it necessary to run the rolls slowly at the start of the operation while the pressure is being laboriously restored to the correct amount for the job in hand, with my apparatus the pressure is restored to its proper amount instantaneously by the mere turning of the valve to its correct position and the rolls may be put into full speed operation at once. Not only does this effect a saving in man power, conserve time and hence increase the output, but also spoilage of a large amount of paper at the commencement of a run, or after a change, is almost entirely eliminated. Furthermore, because of the fact that the desired calendering pressure may be secured without necessity of adjusting the hydraulic pressure or of changing weights, the operators are enabled to secure a high grade product having the proper finish.

Since the described details of construction and operation are illustrative of merely one selected embodiment of my invention, the scope of the same should be determined by reference to the appended claims, said claims being construed as broadly as possible consistent with the state of the art.

I claim as my invention:

1. In paper finishing apparatus, the combination of a stack of calender rolls, a connection for applying pressure to said rolls, means for adjusting said connection to vary said pressure, and a hydraulic device interposed in said connection, whereby said pressure may be relieved at will.

2. In paper finishing apparatus, the combination of a frame, a stack of calender rolls mounted in said frame, a member for applying pressure to said rolls and connected to said frame, means for adjusting said member to vary said pressure and said connection including a hydraulic cylinder and piston, whereby said member may be extended or contracted at will.

3. In paper finishing apparatus, the combination of a frame, a stack of calender rolls mounted in said frame, a member for applying pressure to said rolls and connected to said frame, said connection including a hydraulic cylinder and piston, whereby said member may be extended or contracted at will, and separate means for adjusting said member whereby pressure on the rolls may be varied.

4. In combination, a frame, a stack of calender rolls mounted in said frame, a pressure-applying member, a pressure multiplying device connected between said mem-

ber and said rolls and operative to apply pressure to said rolls, a turnbuckle arrangement in said member for adjusting the length thereof, a cylinder element and a piston element, said elements being respectively connected to the frame and to said member, and means for supplying said cylinder with pressure to act on said member to make the latter effective to apply pressure to said rolls.

5. In combination, a frame, a stack of calender rolls mounted in said frame, a pressure-applying member, a pressure multiplying device connected between said member and said rolls and operative to apply pressure to said rolls, means for varying the pressure applied to said rolls, a cylinder element and a piston element, said elements being respectively connected to the frame and to said member, a stop for said piston element, means for supplying said cylinder with sufficient pressure to force said piston against said stop and to act on said member to make the latter effective to apply pressure to said rolls, and means for relieving the pressure of said fluid to remove the pressure from said rolls.

6. In combination, a frame, a stack of calender rolls mounted in said frame, a pressure-applying member, a pressure multiplying device connected between said member and said rolls and operative to apply pressure to said rolls, a cylinder element and a piston element, said elements being respectively connected to the frame and to said member, means for supplying said cylinder with pressure to act on said member to make the latter effective to apply pressure to said rolls, and means for relieving the pressure of said fluid to remove the pressure from said rolls, said member comprising two relatively adjustable parts

whereby the length of said member may be manually varied, and the normal pressure adjusted.

7. In combination, a frame, a stack of calender rolls mounted in said frame, a pressure multiplying lever co-acting with said stack for applying pressure thereto, a link train connecting the end of said lever with said frame and including a manually adjustable length-varying arrangement for changing or varying the pressure on said roll to suit different conditions and also including a piston and cylinder constituting a hydraulic link for changing the pressure applied to said link frame from zero to a maximum or vice versa.

8. In combination, a frame, a stack of calender rolls mounted in said frame, and a chain of connections for applying super-pressure to said rolls, said chain including a screw connection whereby the pressure may be adjusted to the proper desired amount and also including a hydraulic cylinder and a piston, whereby the desired pressure may be instantaneously relieved or applied.

9. In combination, a frame, a stack of calender rolls mounted in said frame, and a chain of connections for applying super-pressure to said rolls, said chain including a screw connection whereby the pressure may be adjusted to the proper desired amount and also including a hydraulic cylinder, a piston and a stop therefor, the relative movement of said piston and said cylinder in a direction to increase the pressure being normally prevented by said stop and whereby the desired pressure may be instantaneously relieved or applied and constituting a safety device for yielding when the pressure accidentally exceeds a definite amount.

ERNST MAHLER.
